AUTOMOBILE HOOD ORNAMENT

Glenn Feaster, Youngstown, Ohio

Application June 5, 1950, Serial No. 10,372

Term of patent 7 years

(Cl. D14—18)

To all whom it may concern:

Be it known that I, Glenn Feaster, a citizen of the United States, residing at Youngstown, in the county of Mahoning, and State of Ohio, have invented a new, original and ornamental Design for an Automobile Hood Ornament, of which the following is a specification, reference being had to the accompanying drawing, forming part hereof.

In the drawing:

Figure 1 is a perspective view of an automobile hood ornament embodying my new design;

Figure 2 is a top plan view of the same;

Figure 3 is a rear end elevational view of the same; and

Figure 4 is a transverse section taken along the line IV—IV of Figure 2.

I claim:

The ornamental design for an automobile hood ornament, substantially as shown.

GLENN FEASTER.
